MACHINE FOR PREPARING WALL AND
CEILING PAPERS FOR HANGINGBeatrice Maud Thomas, Pendlebury, Manchester,
EnglandApplication January 3, 1939, Serial No. 249,025
In Great Britain January 13, 1938

6 Claims. (Cl. 91—14)

This invention relates to machines for preparing for hanging, lengths of paper to be used as coverings for walls and ceilings, and has for its main objects to provide improved means for applying adhesive to the paper and for obtaining adhesive-coated lengths in a convenient manner for folding; for trimming the selvedges of the paper; for measuring or marking-off pre-determined, pattern-matched or other lengths of paper; for guiding the paper as it passes to the trimming means; for severing the measured lengths of paper, and for cutting strips or bands of narrow-width paper. A minor object of the invention is to provide all these improvements in combination in a portable, collapsible machine which may be conveniently carried from place to place where the paper-hanging is to be done, and may readily be set up for use in those places.

In the accompanying drawings, the various features of the invention are illustrated by way of example, both in combination in a single machine, and separately for use selectively, since any one or more of the improvements may be adopted independently of the others.

Fig. 1 is a side elevation of a collapsible portable wallpaper trimming and pasting machine embodying the invention, the machine being set up for use; and

Fig. 2 is a plan of the trimming and pasting machine.

Fig. 3 is a front elevation, to a larger scale, of means for applying the adhesive to the paper.

Fig. 4 is a broken view illustrating means for trimming the edges of the paper;

Fig. 5 is an end elevation of the edge-trimming means.

Fig. 6 is an elevation, partly in section, to illustrate means for guiding the paper with respect to the edge-trimming means.

Fig. 7 is a perspective view illustrating two forms of means for use in severing narrow-width strips or bands, such means being in the operative position; and

Fig. 8 is an end-view of one form of means for severing narrow-width strips or bands.

Fig. 9 is a perspective view showing the strip-severing means in an inoperative position, and also showing one form of cutting-off means;

Fig. 10 is a further perspective view illustrating other means for use in the obtaining of narrow-width strips or bands;

Figs. 11 to 14 are end views of various forms of strip severing or marking means.

Fig. 15 illustrates a still further alternative for strip-severing or marking.

Referring to Figs. 1 and 2 more particularly, the improved machine, in the form illustrated, comprises an operative portion denoted generally by the reference A and a supporting portion

denoted generally by the reference B, these two portions being detachable one from the other.

The operative portion comprises a framework having end plates or castings 1 and three tie bars or rods 2, said rods having screwed ends on which the end plates are located between nuts 3. Alternatively the tie rods could have reduced ends or could carry shorter tubes, and the plates be located against the shoulders formed by the larger diameters of the tubes. Supported on the two lower tie bars 2, and held in position by screws 3 in the end plates 1, is a trough 4 for the adhesive, in which trough is rotatably mounted a pasting roller 5. The said roller 5 is carried in bearings 6 on the ends of the trough 4, the trough, bearings, and roller, being removable as a whole from the framework, and one of the bearings 6 being open so that the roller may readily be removed from the trough. As shown, the trough has a part of its upper wall cut away at 4^a to facilitate its being filled, and has its end parts of narrower width (for a purpose herein-after set forth), and it is also provided with reinforcements on its under face to contact with the tie bars 2 on which it is supported. The pasting roller 5 is covered with a coarse woven fabric to assist in carrying adhesive.

Above the pasting roller 5 is a pressure roller 7, this being shorter in length than the pasting roller and shorter than the normal width of paper to be treated, and having extended hollow trunnions 5^a by which it is mounted on a non-rotating rod 8, the ends of the rod normally lying in open slots 9 in the upper edge of the end plates 1. Such pressure roller 7 is drawn against the pasting roller 5 by means of springs 10, which operate between the said rod 8 and abutments 11 engaging the lower edges of the end plates 1. Adjacent the said open slots 9 are shorter slots 12 in upwardly extending parts of the end plates 1, into which shorter slots the rod 8, carrying the pressure roller, may be placed when it is desired to release the paper or pasting roller from pressure, the said springs 10 then serving to retain the rod 8 in such shorter slots.

By making the pressure roller shorter in length than the pasting roller, and shorter in length than the width of the paper to be treated, there is no risk of its picking up adhesive from the pasting roller and transferring it to the pattern side of the paper.

On the ends of the pasting roller, are serrated raised parts 13, and on the extended trunnions of the pressure roller are rubber-tired discs 14, these being slidably keyed to the said trunnions so that when in one position they will ride on the said serrated parts 13, and thus lift the pressure roller slightly from the pasting roller, which results in there being a heavier layer of adhesive applied to the paper, whilst when in positions

clear of those raised parts 13, they allow the springs 10 to have their full effect on the pressure roller. The said abutments 11, to which the springs 10 are connected, are, in actuality, the ends of a rod 15, extending across the machine below the trough 4, and the lower faces of the end plates 1 are serrated or scalloped to receive such rod in a number of varying positions with respect to the pressure roller 7, each of which positions brings about a different degree of tension in the springs 10, and thereby varies the compression of the rubber tire of the discs 14 and of the raised parts 13 on the pasting roller 5, to vary the amount of adhesive applied to the paper.

Projecting inwardly from each end plate 1, is a cranked spindle 16, adjustable inwardly, outwardly and rotatably, being held in the set positions by the screws 17, and each such spindle carries at its inner end a flexible flap 18 adapted to bear against the margins of the paper as it passes around the pressure roller 7, and thus remove any surplus adhesive.

Mounted in bearings 19 in the end plates 1 is a supporting roller 20, the end and centre portions of whose periphery, at least, are roughened, as by knurling. Within each end of such supporting roller, at a distance from the extremity, is a wall 20^a which, in addition to supporting the roller on the spindle 21, serves as an abutment for a compression spring 22. As will be seen more particularly from Fig. 4, the spindle 21 is formed with a keyway at its ends, and each end carries a slideable cutting disc 23 which, by the spring 22 is normally pressed against a complementary cutting disc 24 on a boss or hub 25 rotatably mounted on a stud 26 projecting inwardly from the end plate 1. The two cutting discs 23, 24 serve as selvedge trimmers.

The said boss or hub 25 carries at its inner extremity a rubber tire 27 adapted to press against the roughened surface of the supporting roller 20, or the paper thereon, and the boss, with the cutters and the tire, is maintained in position against the pressure of the spring 22, by a bracket 28 which is slideable on the stud 26 and may be held in any desired position by the screw 29. The bracket 28 has two fingers 30 and 31, the lower one of which, 30, is the wider and is curved downwardly to direct the severed selvedge or margin downwards through the frame, whilst the upper one, 31, is the narrower and lies over the upper tie rod 2 to prevent accidental rotation of the bracket 28 about the stud 26, due to the weight of the selvedge-guiding finger, should the screw 29 be left loose. The front portion of the trough 4 is foreshortened at the ends, as above explained, to accommodate the selvedge-guiding means whilst allowing the trough to rest on the adjacent tie rod 2.

From a consideration of Fig. 4, it will be observed that, for each edge of the paper, the two cutters 23 and 24, together with the rubber-tired boss 25, which acts as a driver for the upper cutter, and also the selvedge-guiding finger 30, may be moved as a single unit to any desired position first by the mere slackening of the screw 29 and then by either allowing the spring 22 to move the unit outwards, or by pushing the unit inwards, until the desired position is reached, whereupon the screw 29 is tightened again.

Carried in forwardly-extending parts of the end plates 1, is the means for receiving the roll of paper to be treated and for guiding it to the selvedge trimmers, such means being adjustable to various width of paper.

As shown in detail in Fig. 6, there is provided a roll-supporting rod 32, rotatably located in externally-screwed bushes 33, each of which bushes has two parallel faces by which it is non-rotatably but slidably held in the slots 34 in the end plates. The rod 32 is axially captive in one bush 33, being retained therein by an enlargement or collar 35, and a nut 36, but at the other end the bush 33 is slidably withdrawable from the rod 32, when lifted out of the slot 34, to allow the placing of a roll of paper on the rod, that end of the rod being bluntly pointed. By preference, the removable bush 33, is held captive to the end plate 1, as by the chain 37 and nut 38.

Each bush 33, is fitted at the inner end, with a flyer plate 39 loosely rotatable thereon, and each bush is provided also with a disc-like nut 40, which nuts, by being screwed back against the inside faces of the end plates 1, determine the distance between the two flyer plates 39, which plates therefore may be screwed close up to the ends of the roll of paper and prevent lateral movement of the paper with respect to the selvedge trimmers. The propinquity of the flyer plates 39 and the selvedge trimmers 23, 24, ensures the continuous register of the selvedges with the trimmers.

Extending across the machine and carried by the end plates 1, is a grooved bar 41, the purpose of which is explained below, whilst parallel with and in close proximity thereto is a further bar 42, of square section for the greater part of its length, but of round section for a short distance near each end. The bar 42 may carry some or all of a number of devices such as are illustrated in Figs. 7 to 15. All such devices have a body 43, with a square hole to slide on the bar 42 whereby they are held in operative position, as in Figs. 7, but when moved on to those parts of the bar 42 which are of round section, they fall to an inoperative position, as in Fig. 9. Alternatively the body 43 may have an open slot so as to be passed over parts of the bar 42 of smaller section, and then moved endwise to engage the parts of larger section.

One of such devices comprises a pair of co-operating cutting discs 44 in spring-pressed engagement with each other, which may be employed for severing the web of pasted paper into narrow-width bands as illustrated for example in Fig. 9. This operation is to be distinguished from selvedge-trimming, since the latter cannot be carried out effectively in a machine of this class, on paper which has been pasted.

Another of such devices consists of a spiked roller 45 suitable for perforating papers which cannot conveniently be dealt with by the cutters 44, of which perforating devices there may be two; whilst other devices comprise the knife blade 46, the wire marker 47, the pencil 48 and the marking wheel 49. The marking devices may, as illustrated in Figs. 13 and 14, be arranged for use before as well as after pasting, since they do not pierce the paper and therefore would not allow adhesive to reach the pattern side.

Referring again to Fig. 2 there is shown a collapsible measuring device 50, for example a telescopic or an articulated member, one end of which is detachably held in jaws 50^a in one of the end plates 1. On the other end plate 1, substantially opposite the jaws 50^a is formed a small horizontal web part 50^b for a purpose hereinafter explained.

The supporting portion of the machine com-

prises the box and lid 51, 52, of a carrying case, hinged together at one end and these are adapted to contain the operative portion (including the collapsed measuring member 50) and the table described below.

The box and lid 51, 52, when in the supporting position, constitute parts of an A frame, held in fixed angular relation by the link or hook 53. On the upper end of the lid 52 are projecting ears 54, under which one of the lower tie bars 2 of the operative portion may engage, the other lower tie bar resting on the box 51 (see Fig. 1). Extending from the box 51, and detachably housed in sockets 55 thereon, are two arms 56, on which is slidably placed a hinged table 57, stops 58 limiting the approach of the table to the operative portion of the machine. The table 57 is in two parts hinged together to allow its being placed in the box or lid.

In operation, for preparing full width wallpaper for hanging the rod 32 is lifted to detach the loose bush 33 from the end plate 1, the bush is then drawn from the rod 32, the roll of paper is placed upon the rod 32 and the parts 32 and 33 are then replaced. The flyer plates 39 are urged against the ends of the roll of paper by means of the nuts 40. The selvedge trimming cutters 23 and 24 are then set to the correct position for severing the selvedges of the paper on the roll, the paper is fed between the rubber tires 27 and the supporting roll 20 to effect such severance, and from thence it passes between the pasting roller 5 and the pressure roller 7. The flexible flaps 18 wipe the margins of the trimmed paper, and the paper may then be drawn forwards over the pressure roller 7 and over the operative part of the machine towards the table 57.

It will thus be seen that the machine is operated merely by drawing the paper through it, and that the pasted paper emerges from the machine in a substantially horizontal direction with the pasted side uppermost. This lends itself to the usual custom of paper hangers, according to which a pasted length of paper is given a long fold at one end and a short fold at the other end to facilitate its being carried to the wall or ceiling to which it is to be affixed. By drawing the paper over the table 57 to the correct distance and then folding back the outer end so as to lie in a double width on the table, and by then severing the paper from the supply roll by drawing the rotating knife 59 along the grooved bar 41, and thereafter folding back the severed end so as to lie over the central part of the severed length, the paper is in the disposition usually adopted in the hand treatment of paper, that is with a long fold and a short fold. The table, as will be seen from Fig. 1, need only be quite short, even for cut lengths of several feet.

Should it be desired to obtain narrow width strips, say half width strips, the rotating cutters 44 are placed in the desired position, and the paper, on leaving the pressure roller 7, passes between such cutters and is thereby divided longitudinally.

Assuming the paper to be a patterned paper, the side-by-side lengths of which are to be matched, the improved machine facilitates such matching. When threading up the machine, a distinctive portion of the pattern is cut from the paper and fixed on the horizontal web 50^b of one

end plate, and the paper is then drawn from the machine to the required length which has been marked at 59 on the collapsible measuring device 50. Before severing, the paper is now drawn a further distance until the part of the pattern on the said horizontal web 50^a has its replica in line in the length of paper. The point to which the free end of the pasted strip now extends is marked on the measuring device 50 at 60, and for further lengths it suffices merely to draw the paper each time to such further mark 60 and then sever it on the grooved bar 41, the distance between the first and second markings representing the surplus required to effect matching of the pattern.

In a modification not illustrated the grooved bar 41 and the bar 42 may be combined into one, but this may necessitate the removal of the adjustable devices before severance of the pasted strip can be effected.

What I claim is:

1. In a wall paper pasting machine, a paste-holding trough, a pasting roller rotatable therein, a pressure roller above the pasting roller, the pasting roller being of greater length than the width of paper to be treated, and the pressure roller being of shorter length than the width of the paper to be treated, and flexible means for wiping the margins of the pasted face of the paper as it passes around the pressure roller, for delivery in a substantially horizontal position, pasted side uppermost.

2. Means according to claim 1 wherein the trough and pasting roller is removable from the machine as a whole, whilst the pressure roller is independently mounted in the machine.

3. Means according to claim 1, wherein the pasting roller and pressure roller have co-acting resilient parts, and wherein adjustable tensioning means is provided to vary the compression of such resilient parts to vary the amount of adhesive applied to the paper.

4. A wall paper pasting and trimming machine, according to claim 1, having a support extending across the machine beyond the pasting roller, and having means adjustable along the support for marking the pasted strip to obtain narrow width lengths, the support being of varying section, so that the means for marking the paper are held in an operating position when on a part of one section, and fall to an inoperative position when on a part of another section.

5. A wall paper pasting and trimming machine, according to claim 1, having a support extending across the machine beyond the pasting roller, and having means adjustable along the support for severing the pasted strip to obtain narrow width lengths, the support being of varying section, so that the means for severing the paper are held in an operative position when on a part of one section and fall to an inoperative position when on a part of another section.

6. A wall paper pasting and trimming machine, according to claim 1, having a support extending across the machine beyond the pasting roller, and having means adjustable along the support for perforating the pasted strip to obtain narrow width lengths, the support being of varying section, so that the means for perforating the paper are held in an operative position when on a part of one section and fall to an inoperative position when on a part of another section.

BEATRICE MAUD THOMAS.
